BATHING SUIT

Sam S. Rubino, Chicago, Ill.

Application February 19, 1934, Serial No. 711,857

1 Claim. (Cl. 2-67)

This invention relates to bathing suits and has for its object to provide a bathing suit which can be readily and inexpensively manufactured and which embodies a construction which provides greater leg freedom for the wearer, and other advantages which will hereinafter appear.

The invention will more completely be understood from the following description of a preferred embodiment thereof, taken in conjunction with the accompanying drawing in which,

Figure 1 is a front elevational view of a bathing suit embodying the invention;

Fig. 2 is a fragmentary side elevation thereof, partly in section, and

Fig. 3 is a view of the lower part of the bathing suit, part of which is unfolded for the purpose of disclosing internal construction.

Referring to the drawing, the bathing suit comprises the usual shirt 10 which is provided with the normal skirt 11 which extends over the lower portion of the torso. As indicated in Fig. 1, the shirt is provided with shoulder straps 12 defining arm openings 13. The shirt may also be provided with openings 14 for exposure of the wearer to sunlight, although the invention is not concerned with any particular type of superstructure of the bathing suit. The bathing suit comprises one other part, a central crotch piece 15 which bridges the lower opening of the garment, providing leg openings 16 on either side between the crotch member and the side of the skirt 11. The crotch piece 15 extends upwardly both in front of and behind the wearer and preferably terminates approximately at waist line. The upper ends of the crotch member 15 are stitched to the front and rear wall of the shirt, the stitching being preferably located horizontally, as shown at 17. At its lower edge the skirt 11 is stitched to the crotch member 15. This stitching is located quite close to the edges of the crotch piece 15, and preferably also quite close to the lower edge of the skirt 11.

This stitching is indicated in the drawing by the reference numeral 18, and it will be seen that the stitching comprises four spots adjacent the lower edge of the skirt 11 and adjacent the outer sides of the crotch piece 15. The crotch piece 15 may be fabricated from a plurality of panels stitched together in known manner, the seams providing the necessary reinforcement of this panel.

It will be seen that the leg openings 16 are defined by the skirt 11 and by the crotch piece 15. Since these elements are connected together at isolated points, that is, at 18, very little restriction of the movement of the part 18 is provided by

the remainder of the structure. Owing to this the bathing suit exerts no restriction to the free movements of the legs during swimming.

If desired, further means of securing the crotch piece 15 to the skirt 11 may be provided. Thus, at a height intermediate between the lower edge of the skirt 11 and the stitching 17 I may secure tapes 19 to the edges of the crotch piece 15. These tapes extend horizontally and are preferably anchored to the skirt 11 at the side seams 10 thereof, as indicated at 20. This manner of securing the tape to the crotch piece and the skirt does not impair the freedom of movement of the wearer's legs and at the same time prevents the crotch piece from buckling or folding transversely 15 during swimming.

One great advantage of the present suit is that the skirt effect is always maintained owing to the manner in which the skirt is attached to the crotch member. Owing, however, to the isolated 20 manner in which the skirt is attached to the crotch member, the free-hanging skirt effect is maintained to a remarkable degree, there being so seams or attachments between the waist line and the lower edge of the skirt. One great advantage 25 of the present invention is that the suit can very easily be manufactured. The suit comprises two portions only which can be manufactured separately and the final operation embodies the stitching of them together. 30

Although the invention has been disclosed in connection with the specific details of a preferred embodiment thereof, it must be understood that such details are not intended to be limitative of the invention except in so far as set forth in the 35 accompanying claim.

Having thus described my invention, what I claim as new and desire to secure by Letters Patent of the United States is:

A bathing suit comprising a body portion having a skirt dependent therefrom adapted to surround the lower portion of the torso, a relatively long crotch piece having parallel ends, which ends are permanently attached by horizontal stitching to the front and rear walls of the skirt at an elevated position thereof, said skirt and said crotch piece being stitched together at localized points on the opposite margins of the crotch piece and adjacent the lower hem of the skirt, the sides of the crotch piece between said localized points and the ends of the crotch piece being freely movable with respect to the skirt, and tapes securing the crotch piece to the skirt at points remote from the crotch piece. 50
